UNITED STATES PATENT OFFICE.

MAGLOIRE METHOT, OF OTTAWA, ONTARIO, CANADA.

SWITCH.

1,286,585.

Specification of Letters Patent.

Patented Aug. 14, 1917.

Application filed January 15, 1917. Serial No. 142,501.

To all whom it may concern:

Be it known that I, MAGLOIRE METHOT, a subject of the King of Great Britain, and resident of 133 Queen street, West, in the 5 city of Ottawa, Province of Ontario, Dominion of Canada, have invented certain new and useful Improvements in Switches, of which the following is a specification.

This invention relates to improvements in 10 switches of the type described in United States Patent No. 1,217,043, Feb. 20, 1917, from which this case has been divided.

The objects of the invention are to permit of the motorman actuating a rail switch 15 without stopping his car, to render the mechanism compact in construction thereby occupying a minimum of space, to obviate jarring on the car during the operation of actuating the switch and generally to adapt 20 the several parts to better perform the functions required of them.

With these and other objects in view the invention consists essentially of the improved construction particularly described 25 and set forth in the following specification and accompanying drawings forming part of the same.

In the drawings,

Figure 1 is a fragmentary sectional elevation of a street car and railway embodying the present invention.

Fig. 2 is an end elevation of the wheels adapted to actuate the switch mechanism.

Fig. 3 is a fragmentary perspective view 35 of the switch and coacting links controlling the actuation of the same.

Like characters of reference refer to like parts in the several figures.

Referring to the drawings, A represents 40 a street car of any usual type and B a railroad provided with switching mechanisms C adapted to be controlled from the motorman's platform D by the manually actuated mechanism E. This mechanism E consists 45 of a pair of wheels 10 and 11 which lie in different vertical planes and are rotatably mounted on the bifurcated ends of the bell crank 12, the arms of which are offset to enable one of the wheels engaging and actuating one of the plungers 31 or 32 of the 50 road switching mechanism C.

This bell crank is rigidly mounted on the shaft 13 rotatably supported by the bracket 14 from the longitudinally extending bar 15 55 carried by the brackets 16 mounted on the underface of the floor of the car A.

The bar 15 is provided with shoulders 17 adjacent to the ends thereof which coact with the brackets 16 and obviate longitudinal displacement of the bar, while the downward motion is controlled by the pins 18 extending through the brackets 16. 60

To obviate jarring due to the upward displacement of the bar 15 I provide spiral springs 19 located between the upper face of 65 the bar and the lower face of the floor of the car.

The shaft 13 is provided with a crank arm 20, which is pivotally connected to one end of the link 21, the other end of which is pivotally connected to one arm of the bell crank 22, rotatably supported by the bracket 23 from the bottom of the car A, the other arm of the bell crank being connected to the lower end of the link 24, the upper end of 75 which is connected to the disk 25 carried by the spindle 26, rotatably supported in the quadrant 27 secured to the car A, adjacent to the control levers, so that actuation of the said disk may be readily accomplished 80 by the driver.

To facilitate rotating the spindle 26 and disk 25 to the desired extent, a lever 28 is provided carrying a suitable detent 29 adapted to engage with the serrations or 85 teeth 30 on the quadrant 27.

As the lever 28 is actuated in a vertical plane, motion is transmitted through the link 24 to the bell crank 22 and thence through the link 21 to the shaft 13, rotating 90 the bell crank 12 in a vertical plane and so positioning the same that one of the wheels 10 or 11 will coact with one of the spring controlled plungers 31 or 32, which actuate the longitudinally extending spindle 33 controlling 95 the operation of the railway switching means C.

This railway switching means C is fully described in my United States Patent No. 1,217,043 and since it does not form part of 100 the present invention, except in so far as it is actuated by the wheels 10 and 11 it is deemed unnecessary to further describe the same.

When the mechanism is in use and a car is approaching a switch, the motorman actuates the lever 28 to bring the desired wheel 10 or 11 into position to engage its coacting plunger and so set the switch in the required manner. 105

It will be readily seen that during the 110 rotation of the bell crank 12, the bar 15 which carries the same will be prevented

from moving longitudinally due to the shoulders 17 engaging with the edges of the bracket 16 and also any tendency of undue motion upwardly on the wheels coacting with their plungers will be overcome by the springs 19, so that displacement of the several parts and jarring to the car is entirely eliminated.

As many changes could be made in the above construction, and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. A device of the class described comprising a bar longitudinally extending and vertically displaceable with relation to the car, wheels carried by the bar lying in substantially parallel vertical planes, means for simultaneously elevating and lowering the said wheels and switch means operated by the said wheels.

2. A device of the class described comprising a bar longitudinally extending and vertically displaceable with relation to the car, resilient means controlling the upward motion of the bar, a pair of wheels carried by the bar adapted to lie in substantially parallel vertical planes, means for simultaneously operating the wheels to elevate one and lower the other, and switch means operated by the wheel.

3. A device of the class described comprising a bar longitudinally extending and vertically displaceable with relation to the car, resilient means controlling the upward motion of the bar, means limiting the downward motion of the bar, a bell crank having offset arms operatively supported from the bar, wheels on the said arms, means for rotating the bell crank in a vertical plane, and switch means operated by the said wheels.

In witness whereof I have hereunto set my hand in the presence of a witness.

MAGLOIRE METHOT.
